DESIGN FOR A CAN OPENER

Harland N. Miller, Bowling Green, Mo.

Application July 12, 1944, Serial No. 114,376

Term of patent 3½ years

(Cl. D22—2)

To all whom it may concern:

Be it known that I, Harland N. Miller, a citizen of the United States, residing at Bowling Green, in the county of Pike and State of Missouri, have invented a new, original, and ornamental Design for a Can Opener, of which the following is a specification, reference being had to the accompanying drawing, forming a part thereof.

I claim:

The ornamental design for a can opener, as shown.

HARLAND N. MILLER.
